HEAT-DIFFUSER AND WATER-BACK DEVICE

George Faulds, Philadelphia, Pa.

Application January 7, 1939, Serial No. 249,675

6 Claims. (Cl. 122—20)

This invention has reference to furnaces preferably, although not essentially, of the type used for heating domestic and similar boilers, and it has for a fundamental object to provide a novel heat-diffuser and water-back device for installation in the combustion chamber of such furnace, whereby more complete combustion of the available heat units is positively obtained and the thermogenic effect applied to greater advantage.

Another object is the provision of a device of the above indicated character which is adapted for easy assembly in the combustion chamber of conventional heaters with a minimum of labor and expense while being reversible without in any way impairing its efficiency.

A further object is to provide a combination heat-diffuser and water-back, preferably for domestic heaters, for application proximate the inner upper surface or crown of the combustion chamber whereby said crown is concurrently heated with the surrounding wall when the heater is "on", so that the fluid agency is more promptly heated and circulated than heretofore, whereas when the heater is "off" a sudden drop in the temperature of said agency is prevented.

A still further object is to provide a device of the above indicated type for intermittently-fired furnaces whereby convection losses, during the "off" periods of the heat producing medium, are reduced to a minimum or substantially eliminated.

With the foregoing objects and ancillary advantages in view, this invention, generally stated, consists of the novel means, combinations and arrangements of parts hereinafter described, illustrated by the accompanying drawings, and more particularly defined in the concluding claims.

In the drawings:

Fig. I is a broken vertical section of a standard type of domestic heater with a typical embodiment of this invention installed in the combustion chamber thereof.

Fig. II is a plan section, taken approximately as indicated by the arrows II—II in Fig. I.

Fig. III is a vertical section on the plane III—III of Fig. II, but drawn to a larger scale for clearer illustration of the details.

Fig. IV is a corresponding view to the preceding, but showing the combined heat-diffuser and water-back device of this invention reversed or in a different position.

Fig. V is a top perspective view of a heat retainer component of the novel device of this invention.

Fig. VI is a similar view to the preceding, but looking into the reverse side thereof.

Fig. VII is a perspective view of a supporting bracket later on fully described.

Fig. VIII is a perspective view of an expansion-contraction component of the device supporting means.

Fig. IX is a detail perspective view of one of the baffles included, or used with the heat-diffuser of this invention; and,

Fig. X is a view similar to Fig. III of a modified form of the invention.

More specifically, the present invention is directed to a simple and highly efficient heat-diffuser and water-back device which is capable of easy installation in coal, coke or oil-fired furnaces either as an attachment for existing heaters or for inclusion in new ones. As a convenient embodiment, and referring first to Figs. I—IX, inclusive, the invention is shown as adapted to a coal-fired heater 1, having an ash-box 2, grate 3, combustion or furnace chamber 4, hot water boiler 5, insulating jacket 6, water-head 7, upper and lower access doors 8, 9, respectively, and a clean-out door 10; all of said parts being merely referred to as a back-ground in explaining the present invention.

The novel heat-diffuser and water-back of this invention preferably comprises a concavo-convex body or device 11, of substantial proportions capable of retaining heat and being formed with a surrounding flange 12, in turn including a rim 13 at right-angles to said flange and projecting beyond both faces thereof, for a purpose later on explained, and also to render the device 11 reversible. Axially the device 11 is provided with an aperture 14 having concentrically related outer and inner annular ribs 15, 16, respectively, as well as a series of surrounding spaced sectoral-section passages 17, the angular portions whereof are outwardly directed; and a plurality of diametrically-opposing embossments or apertured lugs 18.

Adapted for seating engagement over either of the annular ribs 15, 16 is a hollow semi-spherical water-back 19 having a concentric groove 20 projecting from the convex face for coaction with said ribs, as clearly understandable from Figs. III and IV, more particularly. This water-back 19 is provided interiorly with semi-crescent radial webs 21, to enhance its heat conductivity, and a flat wall 22 having a central screw-threaded hole 23 for attachment of a service or water-inlet pipe 24, and an axially aligned correspondingly threaded hole 25 for similar connection of an

outlet pipe 26. In addition, the water-back 19 may be provided with a further screw-threaded hole 27, normally closed fluid-tight by a removable plug 28, whereby provision is made for variable connection of either the inlet or outlet pipes 24, 26 in the event the former or the latter should enter the furnace at different levels to those shown.

For the purpose of supporting the device 11, centrally within the furnace 4, in close proximity to the water-head 7, use is made of counterpart brackets 29, one of which is shown detached in Fig. VII. Each bracket 29 comprises a body portion 30 having an extension 31 at one end, with 5 elongated vertical slots 32 therethrough for passage of securing means 33, whereby the respective brackets are attachable to the side walls of the upper access door opening 34; and an opposing arcual portion 35 with spaced radial notches 36 in the upper edge thereof. The bracket 29 also embodies a lateral portion 37 of appropriate transverse-section for abutment against the inner wall of the jacketed furnace 4, and a reinforcing web 38. It is to be noted the curvilinear contour 15 of the lateral portion 37 conforms somewhat with the circumferential outline of the rim 13 of the device 11, so that the latter can seat thereon with provision of inner and outer clearance; or, in other words, the cross-section of the bracket ar- 20 cual portion 35 is substantially wider than that of the rim 13. It is also to be remarked that when the opposing brackets 29 are mounted, as above explained, the inner ends of their arcual portions 35 do not meet, or are spaced apart for 25 interposition of a complementally curved section 39, Fig. VIII, having flanking reduced flanges 40 with elongated horizontal slots 41 for free passage of clamp means 42 engaged in spaced holes 43 through the ends of said arcual portions, 30 whereby effective provision is made for relative expansion and contraction of the brackets 29 and section 39. The section 39 is also provided in its upper edge with a notch 44 similar to the bracket notches 36.

Substantial heat-retaining baffles 45, each having a grooved base 46, Fig. IX, and a tangential blade 47 inclined upwardly to the horizontal and projecting beyond the base 46 at one side, are arranged to seat around the rim 13, of the device 11, so as to provide overlaps defining restricted 50 flow passages 48 for combustible gases under whorling action; while the outer flange 49 of the base 46 may be made deeper than the inner flange for stabilizing purposes.

Fig. IV differs only from the preceding description by showing the inverted usage of the device 11, or the suspension thereof by means of hangers 50 and lock nuts 51 from the brackets 29, said hangers passing through the bores 52 of the apertured lugs 18 and having hook ends 53, for their support by cross-rods 54 seated as desired in the bracket notches 36, as clearly apparent without further explanation. It is to be observed, however, in assembling this embodiment of the invention that, due to inversion of the device 11, the inlet pipe 24 is connected into the hole 25, with the outlet pipe similarly secured in the hole 23.

Referring now to Fig. X, all parts having 70 equivalents in the preceding description are correspondingly designated by the same reference characters, with an added prime exponent for illustrative differentiation and to avoid unnecessary repetitive description. The characterizing distinction of this form of the invention is that

the heat-diffuser and water-back are embodied as a unit 55. This unit 55, it is to be noted, is of substantial cellular structure to embody intercommunicating inlet and outlet hollows 56, 57, respectively, with a surrounding hollow 58 5 and connecting passages 59, so that provision is made for an ample quantity of water to be continuously heated as it circulates through the unit 55. Furthermore, it will be obvious this modification of the invention may be supported either 10 as described in connection with Fig. III or Fig. IV.

In operation, it will be readily understood that as the device 11 or unit is heated by ascending flame within the furnace 4 and, incidental 15 to its "massive" or substantial structure, it will become incandescent by storing-up considerable heat-units, while at the same time it will also diffuse the rising combustible gases, under "whorling" action from below said device around 20 and through the baffle flow-restrictive passages 48 directly against the inner surface of the water-head 7 with greater convective effect and resultant prompter heating of the boiler water and its more rapid circulation through the associated 25 radiating system. In addition, jets or serially arranged flows of the combustible gases will pass through the passages 17 or 17' for direct action upon and circulation about the water-back 19 or unit 55; while restricted flows of such gases will 30 pass through the bracket notches 36, 44, or 36', 44' for even distribution below and about the baffles 45, 45', Figs. III and X, respectively. Thus it will be seen that by the use of the device 11, or the unit 55, and in either of the positions set 35 forth, considerable heat will be accumulated and directed against the inner crown surface of the furnace 4 irrespective of the specific firing agency employed or its continuous or intermittent action, whereby said surface will be rapidly 40 heated and so maintained during the "on" periods of the heater 1; also, when the firing is intermittent incident to the massive or substantial character of the device 11 or unit 55 rapid drops 45 in temperature of the water-head 7 or 7' as well as the water-back 19 or unit 55 will be prevented.

From the foregoing it will be apparent that while specific forms of this invention have been disclosed, other types and modifications thereof in adapting the same to different applications 50 are contemplated. Hence the right is reserved to all reasonable changes in the details of construction and arrangements of the parts as fairly come within the scope of the following claims and the prior art permits.

Having thus described my invention, I claim:

1. In a furnace, a combustion chamber having an access door, a combined heat-diffuser and water-back device adapted for location centrally within said chamber over the combustible medium, said device comprising a substantial structure with surrounding tangential edge-lapping baffles, said baffles being inclined to the horizontal and also capable of storing heat, and bracket means including counterpart components with an intervening section for combined support of the device from the frame of the access door, said intervening section having relatively movable connection with the counterpart component free ends to accommodate expansion and contraction of the combined supporting means.

2. The combination of claim 1 wherein each bracket counterpart component embodies a body portion having an attaching section at one end with elongated vertical slots therein to permit

vertical adjustment, and an arcual continuation at the other end, said continuation having spaced holes proximate the free end for connection of the intervening section.

5. 3. The combination of claim 1 wherein the bracket means intervening section is of curvilinear contour with flanking reduced flanges, and said flanking flanges have elongated horizontal slots therethrough for the purpose specified.

4. The combination of claim 1 wherein the combined heat-diffuser and water-back device comprises a substantial concavo-convex body with a surrounding flange having a circumferential rim projecting angularly beyond the plane of said flange at both sides thereof whereby said device is usable in inverted position, and

the water-back portion is in the form of a hollow semi-spherical structure axially secured within the concavity of the heat diffuser body.

5. The combination of claim 1 wherein the heat-diffuser and water-back device is provided with diametrically opposed vertical borings, and hook-ended hanger members engage through said borings for suspension of the device from and below the bracket means in inverted position.

6. The combination of claim 1 wherein the heat-diffuser and water-back device is in the form of a unit of a cellular structure, said structure being provided with intercommunicating inlet and outlet hollows, and a surrounding hollow with connecting passages for circulatory flow therethrough of the water to be heated.

GEORGE FAULDS.
